UNITED STATES PATENT OFFICE.

JOHN ALEXANDER FORBES, OF DOVER, DELAWARE.

SASH-FASTENER.

SPECIFICATION forming part of Letters Patent No. 509,304, dated November 21, 1893.

Application filed March 11, 1893. Serial No. 465,579. (No model.)

To all whom it may concern:

Be it known that I, JOHN ALEXANDER FORBES, a citizen of the United States, residing at Dover, in the county of Kent and State 5 of Delaware, have invented a new and useful Combined Sash Lift and Lock, of which the following is a specification.

This invention relates to a combined sash lift and lock, and has for its object to provide 10 a sash lift which will not interfere with the use of window-screens, and that will also lock the lower sash to the sill in a substantial and secure manner so as to allow of the upper sash being left open when the lower sash is locked 15 fast.

With these and other ends in view, the invention consists of the construction and arrangement of the parts thereof as will be more fully described and claimed hereinafter.

20 In the drawings: Figure 1 is a perspective view of a window sash and frame, showing the improved device applied thereto and broken away in parts to illustrate the mode of securing and operation thereof, a part 25 of the device being shown in dotted lines. Fig. 2 is a transverse vertical section on the line $z-z$, Fig. 1, on a considerably enlarged scale. Fig. 3 is an enlarged plan view of the lock, showing the same in catching position in full 30 lines and in releasing position in dotted lines, and the outer part or face-plate carrying the lift detached. Fig. 4 is a front view of the lock, illustrating the catches in dotted lines and also the manner in which the same are 35 operated upon by the sash lift.

Similar numerals of reference indicate corresponding parts in the several figures of the drawings.

Referring to the drawings, the numeral 1 40 designates the lower rail of a sash, in which is embedded a box-casing 2, having a rectangular opening 3, at the central upper part of the back of the same and at the inner opposite sides, at or about the centers of the latter, screw-sockets 4 are located. At the center of the lower terminating side of the opening 3, and located within the casing 2, is a space-block 5, of triangular form and having the apex thereof depending toward the bottom 45 of said casing, and on opposite sides of the said space-block are located the shanks 6 of a catch 7, that have engaging shoulders 8 at the

lower ends thereof and are held by the pivot- 55 posts or fulcrums 9, situated a short distance below the said space-bar. The said pivot- posts or fulcrums 9 have their outer ends split to receive the lower ends of springs 10, whose upper free ends bear against the outwardly-projecting ends 11 of the shanks 6. The said shanks 6, below the space-block 5, 60 touch each other, and above the said space-block the said shanks are spread apart and held at a predetermined distance from each other by striking against the opposite sides of the said space-block, in which position they 65 are sustained normally by the action of the springs 10, that bear against the outer edges of the projecting ends 11. The engaging ends of the catches project through the lower end of the casing 2 a sufficient distance and are 70 normally diverged, and are arranged to engage a keeper 12, secured to the sill or adjacent part of the window-frame, and the upper ends of the shanks of said catches are positioned on opposite sides of the opening 3 75 in the back of said casing 2. The said keeper 12 is formed with a suitable slot 13, with which the engaging shoulders 8 are arranged to lock and hold the window-sash closed down, but which may be released to raise the window-sash in a manner which will now be fully 80 set forth.

Over the front of the casing 2 is secured a face-plate or escutcheon 14, having a rectangular slot extending vertically and longitudinally thereof, as at 15, in which is pivotally mounted a combined sash-lift and lock-operating device consisting of an elongated bar 16, having trunnions 17 on opposite sides thereof that are mounted in suitable bearings 90 fixed against the inner surface of the said face-plate. The lower end of said bar 16, on the inner surface thereof, is formed with a curved depression 18, and a widened nose or lower end 19, whereby a convenient finger-grip is provided; and the opposite end of the said bar is of plain form and arranged to pass between the upper divergent parts of the shanks 6 that are located above the space-block 5, and extend through the opening 3 100 to rest against the lower edge thereof and form a stop or reinforce, whereby the sash may be raised by engaging the finger-grip formed as just set forth. To bring the finger-

grip in position for operative engagement, the upper part of the bar 16 is pressed inwardly and goes between the upper diverged parts of the shanks 6, as just stated, and forces the same farther apart and thereby contract or force the lower engaging ends of the catches together to release the same from the keeper 12.

From the foregoing description, it will be seen that the operation of throwing the lift or finger grip into position to raise a sash simultaneously releases the pair of catches from locking contact with the keeper, and hence the device entire is placed upon the lower rail of a window-sash to make it convenient not only as a lock but also to provide means for simultaneously releasing the lock at the time that the grip or lift is engaged.

It will be understood that the device may be applied to any form of window sash and frame, and that the upper end of the bar 16 is the only part of the latter that can be moved inwardly, for the reason that the lower end of said bar, at the outer side of the same, is provided with a small transversely-extending shoulder 20, that is arranged to engage the lower wall of the rectangular slot 15.

It will also be understood that the device may be suitably ornamented, especially the face-plate; and it is obviously apparent that changes in the form, proportion, and the minor details of construction may be resorted to without departing from the principle or sacrificing any of the advantages of this invention.

Having described the invention, what is claimed as new is—

1. In a device of the character set forth, the combination of a sash lock having a pair of catches depending therefrom with shanks extending upwardly into the lock, a face-plate on the outer side of the said lock having an opening therein, and a movable lift pivotally mounted in said opening of the face-plate and arranged to be pressed inwardly at its upper end to engage the shanks of the catches and release the same from an adjacently-situated keeper simultaneously with the positioning of the said lift to release the catches, substantially as described.
2. In a device of the character set forth, the combination of a sash lock with a pair of catches depending therefrom having upward-

ly-projecting shanks, a space-block holding said shanks apart from each other, a face-plate having an opening therein, a lift pivotally mounted in said opening and arranged to lie flush with the face-plate or be depressed inwardly at its upper end to contract or draw the catches toward each other by engaging the shanks thereof, and a keeper with which said catches engage, substantially as described.

3. In a device of the character set forth, the combination of a sash-lock consisting of a pair of shanks divergent at their upper ends and having depending engaging catches, a space-block between the said shanks, a spring or springs engaging the said shanks and normally forcing the same toward the space-block, a casing for supporting said parts having an opening in the back thereof adjacent to the upper diverged parts of the said shanks, and a face-plate applied to said casing having a lift mounted therein that is movable therethrough and arranged to pass between the upper diverged parts of the said shanks and through the opening in the back of the casing to thereby force the engaging catches of the shanks toward each other to release the same from their keeper and to provide a stop for the lift, substantially as described.

4. In a combined sash lock and lift, the face-plate, the movable lift pivotally mounted in an opening thereof so as to lie flush within the opening of the plate when not in action, and the catch or catches connected to the plate and arranged adjacent to the lift so as to be actuated thereby, substantially as described.

5. In a combined sash lift and lock, the casing provided with locking devices or catches to engage the window casing, and the pivotally mounted sash lift arranged adjacent to the locking devices or catches so as to release or engage the same by the raising or lowering of the lift, substantially as described.

In testimony that I claim the foregoing as my own I have hereto affixed my signature in the presence of two witnesses.

JOHN ALEXANDER FORBES.

Witnesses:

PETER L. COOPER,
CHAS. DENNEY.
